UNITED STATES PATENT OFFICE.

EDWARD L. WILLIAMS, OF CHICAGO, ILLINOIS.

ACETYLENE-GAS-GENERATOR LAMP.

SPECIFICATION forming part of Letters Patent No. 618,594, dated January 31, 1899.

Application filed November 15, 1897. Serial No. 658,575. (No model.)

To all whom it may concern:

Be it known that I, EDWARD L. WILLIAMS, of Chicago, in the county of Cook and State of Illinois, have invented certain new and useful Improvements in Gas-Generators, of which the following is a specification.

This invention relates to gas-generators, and more particularly to that class of portable generators which may be conveniently embodied in a lamp for house use or for attachment to vehicles—such, for instance, as bicycles.

My present invention has for its object to provide a generator wherein upon the closing of the controlling-valve the supply of water to the carbid will immediately cease and whereby upon the opening of said valve the supply of water to the carbid will immediately commence again.

To these ends my invention consists in a gas-generator comprising, in combination, a generating-chamber to contain a solid, such as calcium carbid, an elevated water-reservoir to contain a liquid, such as water, a supply-pipe connecting the two and containing a porous material or porous obstructive packing, and a valve located at the discharge end of the supply-pipe.

In the accompanying drawings, Figure 1 represents a sectional view of a portable lamp and generator embodying my invention. Fig. 2 is a detail sectional view of a portion of the same, illustrating a modification; and Fig. 3 is a view similar to Fig. 2, illustrating another modification.

In said drawings I have shown a generator and lamp of the type known as "bicycle-lamps," in which 12 represents the generating-chamber and 13 the perforated tube mounted therein and covered with a fabric 14, while 15 indicates the water-reservoir, which communicates through the supply-pipe 16 with the perforated tube 13, said supply-pipe containing a suitable porous material, such as ordinary wicking 17.

18 indicates the controlling-valve, which is located at the discharge end of the supply-pipe 16 and which may be of any approved construction. In the form shown this valve is the ordinary conical valve mounted on the end of a stem 19, which is threaded through a suitable aperture 20 in the base of the gen-

erating-chamber and is provided with a stuffing-box 21 to prevent leakage and with a hand-grasp 22, by means of which the valve 55 may be rotated. The lower end of the supply-pipe is formed into a suitable seat to receive the valve.

I have found in practice that in lamps of this description, where the valve is located at 60 the upper end or in the upper portion of the supply-tube, when said valve is closed the water remaining in that portion of the pipe or tube below the said valve may still continue to flow, at least to some extent, to the 65 carbide in the generating-chamber, so that the water-supply to the carbide does not cease at once upon the closing of the valve and gas is generated to some extent after said valve is closed. I have also found that after the 70 valve has been closed for some time and it is desired to again generate gas when the valve is first opened the supply of water to the carbide is not immediate, as the water must first percolate through the porous material in the 75 tube or pipe and fill the same before the water issues from the discharge end of the said tube or pipe and has access to the carbide. I have overcome these difficulties by locating the controlling-valve at the discharge end of 80 the supply-pipe, so that as soon as said valve is closed the flow of water to the carbide is at once arrested and the volume of water remains in the supply-pipe, keeping the porous material therein saturated, so that as soon as 85 said valve is again opened the flow of water to the carbide begins at once, and no time is lost in again saturating the porous material.

I have shown and described my present invention as applied to a bicycle-lamp; but it 90 is not limited to this particular application, as it is adapted for use in other lamps which have a supply-tube of considerable length containing a porous material. The form of valve employed may also be varied according 95 to circumstances, the essential feature of my invention being that the valve should be located at the discharge end of the supply pipe or tube. For instance, instead of the conical valve shown a cup-shaped valve 23, adapted to inclose the lower end of the pipe 16 and containing a packing 24, against which said end may abut, may be employed, such a construction being shown in Fig. 2. Moreover,

instead of using the rotary threaded stem for operating the valve other means may be employed for this purpose—as, for instance, such a construction as is shown in Fig. 3, in which 5 a horizontal shaft 25, passing through a suitable stuffing-box and having an external wheel 26, by means of which it may be rotated, is provided at its inner end with an eccentric or cam 27, by means of which the valve 10 may be moved vertically to open or close the lower end of the pipe 16.

I claim—

1. A gas-generator comprising, in combination, a generating-chamber to contain a solid, 15 such as calcium carbid, an elevated reservoir to contain a liquid, such as water, a supply pipe or passage connecting the reservoir and chamber and containing a porous material forming an obstructive packing, and a con- 20 trolling-valve located at the discharge end of

the supply pipe or passage, substantially as described.

2. A gas-generator comprising, in combination, a generating-chamber to contain a solid, such as calcium carbid, an elevated reservoir to contain a liquid, such as water, a supply pipe or passage connecting the reservoir and chamber and having a porous material packed therein, a valve-seat formed at the discharge end of the supply pipe or passage, and a valve provided with a threaded stem passing through a correspondingly-threaded opening in the wall of the generating-chamber and adapted to control the flow of water through the supply pipe or passage, substantially as described.

EDWARD L. WILLIAMS.
